(57) **CLAIM**

We claim the ornamental design for a fold-over cooling pack, as shown and described.

DESCRIPTION

FIG. 1 is a perspective view of a fold-over cooling pack embodying the invention.

FIG. 2 is a front view of the fold-over cooling pack shown in FIG. 1, the rear view being substantially identical thereto.

FIG. 3 is a left side view of the fold-over cooling pack shown in FIG. 1, the right side view being substantially identical thereto.

FIG. 4 is a top view of the fold-over cooling pack shown in FIG. 1, the bottom view being substantially identical thereto; and,

FIG. 5 is a perspective view of the fold-over cooling pack of FIG. 1 in a folded configuration.

The broken lines showing the environment form no part of the claimed design. It is to be understood that the fold-over cooling pack is filled with a deformable gel-like substance and that subtle variations in the surface contours are to be expected.
